FIRE-OPERATED SAFETY DEVICES
Gail L. Bridwell, Orange, Calif., assignor to Safety Engineering Co., Gardena, Calif., a co-partnership
Filed Nov. 15, 1962, Ser. No. 237,979
5 3 Claims. (Cl. 189—45)

Broadly this invention relates to fire operated safety devices. More specifically, the invention is concerned with devices operated by a fire or the heat generated thereby to automatically position a closure, such as a window, in its closed position to minimize the access of air to a fire area.

All of us are quite familiar with the rapid progress of a fire. This rapid progress often closes off escape routes for persons involved and also materially determines the ultimate extent of damage to be caused to a structure. Hence, the desirability of any type of device which can be utilized to minimize the progress of a fire until professional fire-fighters can be summoned to the scene of a fire is well apparent.

It is common knowledge that air or some source of oxygen is required to both sustain a fire and to permit its rapid growth. While many devices have been perfected which function in response to a fire to either extinguish it or delay its progress a relatively few have been developed which are capable of blocking the access of air to the initial fire area. It is obvious that such devices would be extremely effective in limiting the initial progress of the flames to provide both additional time for persons to escape the areas affected and to contain the fire during the sometime relatively long period required for the arrival of professional fire-fighters. This initial retardation of the flames would also serve to provide additional time for detection of the fire before extensive damage has occurred. Often the mere closure of windows and sliding type firewalls would serve to cut off sufficient air to both retard the fire by insufficiency of oxygen and the elimination of sources of drafts which are required to sustain a fire and permit its rapid development.

Accordingly it is an object of this invention to provide a new and improved fire operated safety device.

Another object is the provision of means responsive to fire or the heat from fires to automatically move a closure to its closed position to retard the progress of a fire.

An additional object is the provision of a fire operated safety device wherein a force biased slide means is released by a fire or the heat generated thereby to move a closure device to its closed position.

It is still another object of this invention to provide fire operated safety devices which are inexpensive of manufacture, dependable in operation, readily installed and removed from operating position and one capable of performing properly after long periods of installation.

The manner in which the advantages of the present invention are more particularly realized and its further objects and features achieved will become more clearly apparent from the subsequent detailed description of the invention taken in reference to the accompanying drawing in which:

FIG. 1 is an elevational view of a window as viewed from the inside embodying one form of the present invention;

FIG. 2 is an enlarged partial cross-sectional view of a portion of FIG. 1;

FIG. 3 is a cross-sectional view taken along line 3—3 in FIG. 2;

FIG. 4 is a cross-sectional view taken along line 4—4 in FIG. 2;

2

FIG. 5 is a cross-sectional view taken along line 5—5 in FIG. 4;

FIG. 6 is a cross-sectional view taken along line 6—6 in FIG. 5;

FIG. 7 is a cross-sectional view taken along line 7—7 in FIG. 1;

FIG. 8 is a cross-sectional view of a return mechanism utilized in the device of FIG. 1;

FIG. 9 is an elevational view of the window as viewed from the inside embodying another form of the present invention;

FIG. 10 is an enlarged partial cross-sectional view of a portion of FIG. 9;

FIG. 11 is a cross-sectional view taken along line 11—11 in FIG. 10; and

FIG. 12 is an enlarged partial cross-sectional view taken along line 12—12 in FIG. 10.

The accompanying drawings are primarily intended so as to illustrate presently preferred means of constructing fire operated safety devices falling within the scope of this disclosure. It is to be understood that those skilled in the art to which the invention pertains may effect alterations in the embodiments of the invention disclosed by the use of routine and ordinary engineering skills without departing from the inventive concepts of the device. Also, further equivalent means can be employed in order to accomplish the operations and structural advantages of the invention.

As an aid toward understanding this invention it can be stated in essentially summary form that it involves a bumper device biased by a return spring mechanism to move along a guide track on which it is slidingly disposed toward the spring mechanism upon the destruction by heat of a fusible link attaching the bumper to a fixed object adjacent an end of the guide track remote from the return spring mechanism. In the embodiments shown in the drawings the track is positioned in underlying relation with respect to a frame rail of a sliding window sash assembly so that the bumper device may engage the sash upon release to slide the window to its closed position.

The invention can be more fully understood by referring to the accompanying drawings wherein FIGS. 1—8 show one form of the invention. FIG. 1 is a view of a slide type window 10 as viewed from within a building structure, which embodies a spring biased closure bumper assembly generally designated by the reference character 12. The window 10 is of conventional construction and includes a fixed sash, covering half of the window area, formed by a pane of glass 14 supported by a sealing gasket 16 in frame rails 18, 20, 22 and 24 which are suitably fixedly mounted in a recess 26 of an ordinary window frame including the usual bottom sill member 28 shown in FIG. 3. Window 10 further includes a screen section 30 positioned in a portion of the half of the window adjacent the fixed sash which is provided with a sliding sash 32 that can be moved from a closed position to the open position shown in FIG. 1. Sash 32 includes side rails 34 and 36, top rail 38 and a bottom rail 40, all of which cooperate with a sealing gasket 42 to secure a glass pane 44 within the sash 32. The window assembly further includes the usual framing strips 46.

As can be seen more clearly in FIG. 3, the sliding sash 32 is equipped with a longitudinal slide slot 48 along the bottom edge of the bottom rail 40 which is slidably disposed on an upstanding guide rail 50 carried by the sill portion 28 of the window frame. This arrangement permits the window sash 32 to be moved by simple sliding motion between its open position exposing the screen 30 as shown in FIG. 1 to a closed position to

the right in FIG. 1 which would, of course, close off the screen section and provide along with the fixed sash a completely closed window assembly. The fixed sash is provided with a solid sealing strip 54, shown in phantom in FIG. 3, attached to the side frame rail 24 which cooperates with a similar overlapping sealing strip 56 carried by the left hand side frame rail 34 of the sash 32. One or both of these sealing strips 54 and 56 may be provided with the usual rubber or mohair sealing strips which operate in the usual manner to effect a relatively air-tight seal when sash 32 is pushed to its closed position.

The bumper assembly 12 may be included on the above described window assembly during manufacture or may be installed separately after the window assembly has been in use. As shown in FIGS. 2, 3 and 6 the bumper assembly comprises an elongated guide track 60 forming a straight channel having a bottom 62 and upstanding side members 64 which together with inwardly extending top flanges 66 define internal guide slots 68. Track 60 is disposed on the sill portion 28 of the window frame and partially underlies the bottom rail 40 of the sash 32 and extends in front of the fixed sash from the left hand side of the window assembly as viewed in FIGS. 1 and 2 to a point to the right of the right hand side rail 36 of the sash 32 as seen in FIG. 2.

The guide track 60 slidably supports a bumper 70 by means of laterally extending flanges 72 formed on the bottom of the elongated cylindrical body 74 of the bumper. These flanges 72 are slidably engaged in the guide slots 68 of the track for free sliding movement of the bumper along the track. As may be seen by the dashed lines in FIG. 3, a substantial portion of the front face 74 of the bumper overlaps the bottom edge of the right hand side rail 34 of the sash 32 whereby right hand movement of the bumper along the track 60 causes the bumper to engage the sash 32 for movement thereof to a closed position in a manner to be described. The bumper further includes a recessed rear top portion defined by a rounded wall 76 and a flat bottom surface 78 extending between the rounded wall 76 and the rear face 80 of the bumper.

Bumper assembly 12 further includes a fusible link assembly 82 and a return spring assembly 84. The fusible link assembly includes a first link member 86 having a forward end 88 attached on the recess bottom surface 78 of the bumper by a screw 90 passing therethrough into the body of the bumper, and elongated body portion 92 of the member 86 extends to a free end 94 which includes a central aperture 96. A second link member 98 is attached to the inside surface of the left hand side member 100 of the window frame by suitable means, such as screws 102, includes an offset downwardly extending finger 104 which is received in the aperture 96 of the first link.

The return spring assembly 84 referred to above, comprises a base member 106 which is suitably secured to the sill 28 and positioned to the outside of the sliding sash 32 to provide clearance for a housing 108 supported on the base. In the form of the invention shown in FIGS. 1-8 the assembly 84 is positioned above the sill 28. Structurally the assembly 84 includes a fixed shaft 110 which is provided centrally within the housing and is utilized to support a reel 112 that is connected internally in a conventional manner to a coil spring 114 whose other end is attached to the shaft 110. A cable 116 wound in a clockwise direction on the reel, as seen in FIG. 8, extends through the bottom opening 118 of the housing beneath a headed guide pin 120 in a path immediately above and adjacent to the guide track 60 through an opening 122 in the lower portion of the bumper body to a securing ferrule 124 abutting the rear face of the bumper. It is to be noted that the cable 116 passes beneath the bottom edge of the seal strip 56 on the sash 32 and neither the cable nor parts of the re-

turn spring housing interfere with the normal opening or closing movement of sash 32.

By virtue of the above described arrangement the sash 32 may be operated in its normal fashion without interference from the spring biased bumper assembly 12. However, in the event a fire starts in the room or area adjacent the window assembly, the direct action of the fire or heat from the fire will cause one or both of the fusible links 86 or 98 to melt thereby releasing the bumper which will then be drawn by the cable 116 into engagement with the lower edge of the side rail 34 of the slidably sash 32. Continued movement of the bumper as the cable is wound by spring 114 onto the reel 112 will firmly and positively slide the sash 32 to its closed position. In this manner the window will be automatically moved to its closed condition thereby sealing off a source of air which would otherwise feed the fire or provide a source of draft to permit rapid spread of the fire.

It can be seen that if all windows of a building are thus equipped that the progress of any fire within the building would be retarded thereby providing additional time for its discovery and, very importantly, minimizing its spread until the arrival of persons equipped to properly extinguish the fire.

An additional structural feature comprising the offset bracket 126 is provided as shown in FIGS. 1 and 7. This bracket is secured to the right hand top edge of the sash 32 by screw 128 to provide a guide in cooperation with the front edge 130 of the window frame. The purpose of this arrangement is to prevent the window from jamming due to the force of the bumper being applied to the opposite lower corner of the sash when the fusible link assembly is destroyed in the presence of a fire.

In the described embodiment the fuse link is commercially available and is composed of a Phosphor bronze composition including lead and tin. In a working model of the device of the invention the fuse link was designed to melt at a fairly low temperature in the order of 160° F., which would obviously be well above the normal ambient temperatures encountered in the area adjacent the window. In order to provide adequate assurance against inadvertent fracture of the link but still providing sufficient pull on the bumper to assure proper closing of the sash 32, a pull of approximately ten pounds on cable 116 has been found to be adequate. Accordingly, the link is provided with sufficient strength to withstand such a constant loading.

The embodiment of the safety device described in conjunction with FIGS. 1-8 is intended for use with the return spring assembly 84 in an exposed position extending upwardly from the sill 28. By resort to the arrangement shown in FIGS. 9-12 the return spring assembly can be hidden from view. Again this type of arrangement can be utilized with installed or uninstalled window sash.

As shown in FIGS. 9-12 this embodiment of the safety device differs from the embodiment of FIGS. 1-8 in the structural arrangement required to position the return spring assembly 84 below the surface level of the window sill 28. Otherwise the structure of the remaining elements and the operation of the device are identical to that described in conjunction with the previously described embodiment. In this embodiment the sill structure must be altered from its conventional construction to include a pair of aligned openings 150 and 152 which are rectangularly shaped to accommodate the cross-sectional configuration of the housing 154 of the slightly altered return spring assembly 156 utilized in this type of mounting. This assembly is substantially identical to that utilized for installation in a position above the sill in that it includes a top plate 158 having extension tabs 160 having apertures for receiving securing screws 162 that anchor the assembly to the sill. Also in this

form of the spring assembly the guide pin 164 extends across the housing. This pin, however, is in the form of a centrally disposed roller 166 having, trunnions 168 rotatably disposed in suitable apertures in the housing 154. By disposing the assembly in the openings 150 and 152 of the sill as shown in FIG. 10 the entire assembly is hidden from view. This permits the cable 116 to be trained over the roller 166 and extend through an opening 170 defined by a raised stamped portion 172 of the top plate 158 and along the channel 60 in the same manner 10 as in the previously described embodiment.

In order to provide a sealed or air tight window assembly a small quantity of conventional putty or mastic 174 is applied in the opening 170 after the device is assembled. This small amount of putty provides an 15 effective seal and does not offer sufficient resistance to interfere with normal operation of the device. Further, sealing is provided by the employment of a covering housing 176 which is positioned over lower protruding portion of the return spring housing 154 and secured by 20 means of screws 178 extending through mounting tabs 180 into engagement with the lower face 182 of the sill. It is quite obvious that the remaining structure and operation of this embodiment is the same as shown in FIGS. 1-8.

From the foregoing it is apparent that new self operating safety devices have been provided which automatically close slide operated windows or fire-doors in the event of a fire in their proximity. It is also clear that these 30 safety devices do not interfere with the normal operation of the window on which they are installed prior to the destruction of the securing fuse-links by the action of a fire.

It will be realized by those skilled in the art to which the invention pertains that by ordinary skills a variety of differently appearing fire operated safety devices may 35 be designed and built utilizing the features of the invention as embodied in the above described examples of the devices of the invention. Accordingly, since the structures of this invention are susceptible to such modification the invention is to be considered as being limited only 40 by the appended claims.

I claim:

1. A device responsive to temperatures encountered in fires for moving a sliding closure between an open position to a closed position along a slide path of operation 45 of said device, said device comprising:

bumper means having a contact surface;

guide means supporting said bumper means for sliding movement along said slide path said guide means comprising a track having only said bumper in guiding engagement therewith;

biasing means fixed in position relative to said slide path for moving said bumper means along said path in a direction coinciding with the direction extending between said open and said closed positions; connector means fusible at said temperatures, said connector means having first and second ends, said first end of said connector means being fixed with respect to said biasing means and said second end being connected directly to said bumper means, said connector means holding said bumper means in a remote position relative to said first and second positions whereby fusion of said connector means by said temperatures causes said contact surface to engage said sliding closure to move said sliding closure in response to said biasing means from said open to said closed position.

2. A device as defined in claim 1 wherein said connector means comprises a fusible link connecting said bumper means to a fixed point remote from said first and said second positions.

3. A device as defined in claim 1 wherein said biasing means comprises a spring biased reel including a cable connected to said bumper means.

4. A fire operated window closing safety device comprising in combination:

a window frame adapted to be positioned in a building, said window frame comprising a top frame member and a bottom frame member and end frame members connected therebetween to define the window frame, guide means on said top frame member and guide means on said bottom frame member, said guide means being suited for the guidance of a sash; a window sash mounted in said window frame in association with said guide means, said window sash being so related to said guide means so that said sash is slideable along said guide means from an open position to a closed position, glass positioned within said sash to inhibit the passage of air through that portion of said window frame at which said sash is positioned, further glass positionable within said window frame so that when said sash is in said closed position passage of air through said window frame is inhibited;

heat actuated window closing means mounted in association with said window frame, said heat actuated window closing means comprising a heat fusible link having first and second ends, said first end of said heat fusible link being secured to one of said frame members, a bumper movably mounted for substantially linear motion along a path substantially parallel to the path of travel of said sash, said bumper being movably mounted on one of said window frame members having guide means thereon, said bumper being of such dimension and having its path of motion so positioned with respect to the path of motion of said sash that said bumper engages upon said sash when said bumper is moved along its path, said bumper being secured to said second end of said fusible link, elongated flexible means connected to said bumper, force means connected to said elongated flexible means to urge said bumper means in a direction adapted to cause said sash to be moved towards its closed position, said fusible link restraining said bumper from being moved along its path until said fusible link is melted, whereby said sash may be positioned substantially without regard to said safety device until said fusible link is melted, and when said fusible link is melted said bumper is urged by said force means against said sash to close said sash.

5. The combination of claim 4 wherein bumper track means is secured to said frame member adjacent said sash guide means.

6. The combination of claim 5 wherein said bumper track means comprises an elongated bumper guide track secured to said window frame member, said guide track having upward and inward extending portions defining internal guide slots, said bumper having flanges engaging in said internal guide slots so that said bumper is guided for travel along said guide track.

7. The combination of claim 4 wherein said force means comprises a return spring assembly, said return spring assembly including a coil spring, said elongated flexible member being connected to said coil spring so that said coil spring causes tension in said elongated flexible member, said return spring assembly being secured to one of said frame members.

8. The structure of claim 7 wherein said elongated flexible member is a cable.
